FORMING TUBE FOR GLASS FIBERS

This invention relates to textile carriers and more particularly to a carrier or "forming tube" for use in the winding of freshly spun glass filament or fibers.

In the spinning of glass fibers to be processed into textile material such as yarn and the like, glass in a molten state is drawn through small openings or orifices in a plate commonly referred to as a spinneret into the form of continuous filaments which solidify upon contact with the air. These continuously drawn filaments are wound onto a tubular carrier in the form of a flexible cylindrical sleeve which is generally referred to as a "forming tube". In a glass fiber spinning operation, this forming tube is slipped onto a spindle or the like which is rotated at very high speeds, frequently around 8,000 to 10,000 r.p.m. and up, and the glass filaments are drawn from the spinneret and wound on the tube at a relatively high linear speed generally 10,000 to 12,000 feet per minute and more. These forming tubes are used not only for such a winding operation but for subsequent winding and unwinding operations as well.

Due to the high speed at which the forming tube is rotated and the rugged conditions of use to which it is subjected, these tubes must meet rigid standards and preferably should be of a suitable design and material so as not only to be inexpensive in initial cost but to be capable of repeated use. Furthermore, these forming tubes must be provided with external surface characteristics specifically suitable for the glass fiber winding and unwinding operations for which they are used. In general, it can be said that such tubes are required to have a relatively smooth peripheral surface to permit the glass fibers to be readily unwound from the tube and at the same time this peripheral surface should be sufficiently rough so that satisfactory winding of the fibers on the tube may be accomplished. In addition, these tubes should also be of light weight to avoid deformation by centrifugal force which at the speeds referred to above is of a substantial magnitude. Furthermore, these forming tubes should be highly resistant to compression by the fibers wound tightly on the tube so that the tube maintains its shape after removal from the spindle and the tubes should have sufficient flexibility and elasticity to permit their ready removal from the wound package of glass fibers when the tube is to be reused.

Two commonly employed materials in use today for making such forming tubes are plain paper or paperboard and plastic such as polyethylene both of which have objectionable features. Although a forming tube composed solely of ordinary paperboard generally performs satisfactory the first time it is used, its inherent lack of strength and lack of flexibility causes it to deteriorate rapidly when reused. It is thought that the rapid deterioration of such paper forming tubes occurs primarily as a result of the breaking of the cellulosic fibers in the tube resulting from the bending and folding to which such paper tubes are subjected. Therefore, forming tubes of fibrous material such as paper or paperboard are generally discarded after a few uses or even after a single use adding considerably to glass fiber manufacturing costs even though the initial cost of such paper is low. Forming tubes of plastic have also been used with some success but the severe stresses to which plastic forming tubes are subjected frequently causes plastic tubes to disintegrate or "explode" during use primarily as a result of centrifugal force not only creating a hazard but, as a result of the high initial cost of such plastic tubes, adding considerably to the glass fiber manufacturing costs.

Accordingly, a primary object of this invention is to provide a new and novel nonrigid forming tube for use in the winding of glass filaments or fibers.

Another object of this invention is to provide a new and novel nonrigid forming tube for winding glass fibers which employs a minimum amount of inexpensive materials to provide a forming tube of great strength and flexibility capable of repeated use.

A further object of this invention is to provide a new and novel nonrigid forming tube for winding glass fibers which is low in initial cost, which is easily manufactured on conventional winding apparatus, and which contains a highly suitable winding surface for glass fibers.

Still another object of this invention is to provide a new and novel nonrigid forming tube for glass fibers which is not only capable of high rotational speeds without destruction but which utilizes a combination of materials to prevent spreading of weakened localized areas on the tube such as result from thin spots, tears or the like.

Other objects and advantages of the invention will become apparent from the following description taken in connection with the accompanying drawings.

10 In general, the objects of this invention and other related objects are accomplished by spirally winding at least one strip of fibrous material such as paper and winding thereon a ply of woven textile material such as cloth impregnated with an elastomeric material. A strip of resin impregnated paper is wound spirally over the wound strip of textile material so as to provide a tube having a paper inner ply, an intermediate ply of cloth impregnated with the elastomeric material and a resin impregnated outer paper ply. A spiral wrap of release material is also preferably wound over the resin impregnated outer ply which is removed after the resinous material is cured to provide a hard, smooth external winding surface on the tube for glass fibers.

The novel features which are believed to be characteristic 25 of the invention are set forth with particularity in the appended claims. The invention itself, however, both as to its organization and method of operation may be best understood by reference to the following description taken in conjunction with the accompanying drawing in which:

30 FIG. 1 is a diagrammatic illustration of tube winding apparatus for winding the forming tube of the invention;

FIG. 2 is a sectional view taken substantially along line 2-2 of FIG. 1 in the direction of the arrows;

FIG. 3 is an enlarged perspective view of the tube of the invention wound with the apparatus of FIG. 1;

FIG. 4 is an enlarged sectional view taken substantially along line 4-4 of FIG. 3 in the direction of the arrows; and

FIG. 5 is a sectional view similar to FIG. 4 showing the forming tube of the invention in a collapsed condition.

40 Referring now to the drawings and to FIG. 1 in particular, there is shown diagrammatically a typical spiral tube winding apparatus by means which the winding of the forming tube of the invention is carried out. As previously stated, the forming tube of the invention, which is shown in section in a collapsed condition and designated generally by the numeral 11 in FIG. 5, is of the type which is particularly suitable for use in the winding of freshly spun glass filaments or fibers drawn from the spinneret of a glass furnace (not shown). However, the tube 11 of the invention may also be employed in other glass fiber manufacturing operations involving glass fiber winding and takeoff procedures.

45 As generally illustrative of the method of winding the forming tube 11 of the invention, the conventional spiral tube winding apparatus of FIG. 1 is designated generally by the numeral 12. This spiral tube winding apparatus 12 is of the conventional type and is shown carrying out of a winding operation by means of which a continuous tube T advanced in the direction of the arrow I is produced. The tube T is cut into suitable lengths to form the forming tube 11 of the invention as will be explained hereinafter.

50 As is well known, the spiral tube winding apparatus 12 comprises a frame 12, a stationary mandrel 14 supported on the frame, a flexible endless belt 16 extending around a pair of pulleys 17 at least one of which is driven for rotating and advancing the tube T as it is formed and a cutoff device 18 for cutting the continuously wound tube T into uniform sections of a selected length.

55 In the winding of the continuous tube T, at least one strip 21 of paper unwound from a supply roll 22 is first wound on the tube making mandrel 14. Preferably, two such paper strips are employed and accordingly a second paper strip 23 unwound from a supply roll 24 is wound in overlying staggered relationship with and at the same angle as the strip 21 from the opposite side of the mandrel 12.

In order to adhere the paper strips 21, 23 together in the spirally wound relationship, the paper strip 23 is advanced in contact with an applicator roll 26 suitably supported for rotation in a receptacle 27 containing a suitable adhesive in the well-known manner. Thus, the applicator roll 26, as it rotates, applies adhesive to the underside of strip 23. Contact between the strip 23 and the applicator roll 26 is maintained by advancing the strip 23 under guide rollers 28, 29 also suitably supported for rotation on the receptacle 27. The paper strips 21, 23 are preferably each wound with the edges of adjacent convolutions in an abutting relationship although, it should be understood, that the adjacent edges of the strips 21, 23 may be overlapped if desired. As shown in FIG. 1, the ply formed by strip 21 is provided with a spiral butt seam 21a and the ply formed by strip 23 is provided with a spiral butt seam 23a.

As the spirally wound plies formed by paper strips 21, 23 advance along the mandrel 14 down from the belt 16, a strip of woven textile material 32 impregnated with an elastomeric material is spirally wound in overlying relationship with wound paper ply 23 to form a spirally wound intermediate ply. Any suitable woven textile material may be employed for the ply 32 and in one embodiment, a loosely woven textile material referred to in the textile industry as "osnaburg" cloth provides the novel results obtained with the forming tube of the invention. Preferably, the impregnated cloth strip 32 is wound with the edges of adjacent convolutions in overlapping relationship.

The strip 32 is woven textile material is unwound from a supply roll 33 and is impregnated with an elastomeric material in liquid form by advancing the strip 32 through a receptacle 34 containing an impregnating bath 36 of elastomeric material as shown best in FIG. 2. Any suitable elastomeric material which remains permanently "stretchable" or "rubbery" after curing may be used as the impregnating medium in the bath 36. For instance, polymeric material such as polyvinyl chloride, polyvinyl acetate, etc., may be employed which is of a type available initially in a liquid form for impregnation and which after curing remains in a permanently elastomeric or rubbery state. The elastomeric material used may be of the type curable by any well known curing process such as air curing, curing by solvent evaporation or the like.

Guide rollers 37-40 are suitably positioned as shown in FIG. 2 adjacent the receptacle 34 so that the strip 32 is immersed in the elastomeric material bath 36 and subsequently removed for winding onto the paper ply 23.

An outer ply 41 of fibrous material such as paper, unwound from a supply roll 42 is impregnated with a suitable resinous material is then spirally wound in overlying relationship with the wound impregnated cloth ply 32 as shown in FIGS. 1, 3. The paper strip 41 is impregnated by advancing the strip 41 through a receptacle 43 containing an impregnating resin bath 44. Preferably, the resinous material of the bath 44 is an acrylic resin which is provided in the form of an aqueous emulsion. The curing of this resinous material 44 may therefore be accomplished by the evaporation of the water vehicle from the acrylic resin and water mixture.

Suitable guide rollers are provided in association with the receptacle 43 similar to the arrangement for the receptacle 34 as shown in FIG. 2 which include guide rollers 46, 47 and 48 as shown in FIG. 1. The paper strip 41 is therefore immersed in the resinous emulsion bath 44 and subsequently removed for winding spirally in overlapping staggered relationship with the impregnated cloth ply 32.

In order to provide a hard, uniformly smooth, slick surface on the impregnated paper ply 41 after the resin is cured, a wrapping ply 51 of smooth, slick, release material such as polyethylene, cellophane or the like is unwound from a supply roll 52 and spirally wrapped as shown in FIGS. 1, 3 in overlying relationship with the impregnated outer paper ply 41. The ply 51 is preferably wrapped with the edges of adjacent convolutions in overlapping relationship as shown to form an outer spiral seam 51a completely covering the underlying resin impregnated ply 41. Preferably, the impregnated paper

strip 41 is wound with the edges adjacent convolutions in overlapping relationship as shown best in FIG. 3 to form an outer spiral seam 41a.

With the use of release material for the ply 51, there is no adherence of the release material ply 51 to the resinous material with which the paper ply 41 is impregnated and ply 51 is tightly wound in the spiral winding operation with FIG. 1 with the underlying ply 41 to form the T. The tight engagement of wrapping ply 51 with the impregnated paper ply 41 not only confines the resin within ply 41 but produces a substantially complete engagement between the surfaces of the two plies. As the continuously formed tube T moves in the direction of the arrow I, it enters the cutoff device 18 in which it is cut into uniform sections which are removed for curing. Preferably, these tube sections are formed approximately 8 feet in length. The curing of the sections are severed from the tube 7 is then carried out so that the water vehicle in the resin-water mixture in the tube outer ply 41 will be evaporated and the resin with which the ply 41 is impregnated will set or cure permanently. Using an aqueous acrylic resin mixture for impregnation of the tube ply 41 permits the curing to be accomplished under normal room temperature over relatively short periods of time. However, if it is desired to shorten the curing time by the application of heat, means such as an oven can be utilized. The elastomeric material with which the cloth ply 32 is impregnated is also permitted to cure into a "rubbery" state having a degree of elasticity so as to permit stretching when the cloth ply is deformed. After curing, the wrapping ply 51 of release material is then unwound from each cured tube section and discarded. When the wrapping ply 51 has been removed, it will be noted that the resin impregnated underlying paper ply 41 has been compressed and smoothed so as to provide a hard, relatively smooth slick outer surface. This shiny, slick outer surface on the resulting tube 11 is, in effect, a reproduction of the slick surface of the polyethylene ply 51 so that the entire outer or winding surface of the tube 11 is surface having a smooth, slick appearance and feel. The cured tube sections are then cut into a plurality of short lengths, preferably lengths of approximately 8 inches to provide forming tubes 11 of a length suitable for use in a glass fiber winding and unwinding operation.

It can be seen that the forming tube 11 of the invention is not only characterized by high strength and durability so as to be capable of repeated use with a minimum of deterioration but it may be easily removed from a package of glass fibers wound thereon by collapsing the tube 11. The outstanding feature of the tube of the invention are the new and unexpected results obtained by the novel combination of various materials from which the tube is formed. As is well known, rapid deterioration and/or destruction of forming tubes of the type presently available for the purposes described herein occur primarily from a weakening or splitting of the end edges of the tube which areas spread rapidly throughout the sleeve resulting in ultimate tube destruction. As a result of the elastomeric material with which the cloth ply 32 is impregnated, stress applied to the end portions of the tube of the invention is absorbed as the elastomeric material stretches to permit sliding movement and resultant "bunching up" of the threads from which the woven cloth is formed thereby gradually absorbing and ultimately resisting any deterioration of the tube wall. At the same time, the paper plies on the opposite sides of the impregnated cloth ply 32 retains the impregnated cloth ply sandwiched therebetween forming a laminated structure in which the various laminations in mutually reinforcing relationship. At the same time, the resin impregnated outer paper ply has a smooth, slick surface ideally suitable for the winding of glass fibers.

While there has been described what at present is considered to be the preferred embodiment of the invention, it will be understood by those skilled in the art that various changes and modifications may be made therein without departing from the invention.

I claim:

1. A nonrigid forming tube for glass fibers comprising, in combination, at least one spirally wound inner ply of paper, a spirally wound intermediate ply of woven textile material impregnated with an elastomeric material and a spirally wound outer ply of paper, a said paper plies and said ply of textile material having a thickness and composition for permitting said forming tube to flex readily and collapse longitudinally for removal of the tube from a package of glass fibers wound thereon.

2. A nonrigid forming tube in accordance with claim 1 wherein said spirally wound outer ply is impregnated with a

resinous material.

3. A nonrigid forming tube in accordance with claim 1 wherein said forming tube includes a pair of spirally wound inner plies of paper arranged in staggered, overlapping relationship with adhesive therebetween.

4. A nonrigid forming tube in accordance with claim 2 wherein said outer ply is impregnated with an acrylic resin.

5. A nonrigid forming tube in accordance with claim 4 wherein said outer ply is provided with a hard, smooth exterior winding surface for said glass fibers.
